KNITTING MACHINE

Frank G. Weisbecker, Glenside, Pa., assignor to
 Hosiery Patents Incorporated, Lansdale, Pa., a
 corporation of Pennsylvania

Application January 21, 1937, Serial No. 121,679

58 Claims. (Cl. 66—127)

This invention relates to straight knitting machines, and more particularly to a mechanism for controlling the operation of the yarn carrier bars of a straight knitting machine, for example, of the full fashioned type.

In straight or flat knitting machines now generally used, such for example as those used for producing full fashioned hosiery and other similar knitted articles, the yarn carriers are mounted upon and move with bars that are commonly called yarn carrier bars. These bars may extend for the full length of the knitting machine which is composed of one to thirty or more sections; and each carrier bar has as many yarn carriers as there are machine sections. The yarn carrier bars are reciprocated longitudinally of the machine, and their movement is controlled by stops arranged on the knitting machine.

There have been attempts heretofore to selectively operate certain of the yarn carrier bars in determined order, but in general such attempts have been limited to special rods and for special purposes.

Where the attempt has been made heretofore to provide automatic mechanisms for controlling the selective operation of all of the carrier bars of a straight knitting machine, the mechanisms were found to be unsatisfactory. For example, they provided an automatic control for only the means driving the carrier bars, and the carrier bar stops were left for manual operation. Consequently, when changes in the carrier bar stops were to be made during the knitting operation, the machine had to be stopped to permit the knitter to manipulate the stops. These mechanisms also did not provide a compact control at a single station for the drive of the carrier bars.

It is, therefore, an object of this invention to provide novel mechanism for automatically controlling the selective operation of the usual yarn carrier bars to permit yarn changes and additions as desired without interruption of the knitting machine operation.

It is also an object to provide mechanism for automatically controlling the selective operation of the means driving the yarn carrier bars, which mechanism occupies a single control station to minimize the time required by an attendant in checking, adjusting and repairing the mechanism. In this way, losses due to idleness of the machine, while manual changes in the control mechanism are being made, will be substantially reduced. Much time will also be saved in the inspection of this mechanism as its arrangement permits an

attendant to make a complete inspection from a single station.

Another object is to provide an improved pattern controlled mechanism for selectively operating the yarn carrier bars in determined order.

A further object is to provide pattern controlled mechanism for selectively operating the carrier bar stops in determined order.

Another object is to provide pattern mechanism which is capable of providing a wide variation in the selection and operation of yarn carrier bars and which accomplishes such variation with a minimum amount of mechanism and a minimum number of pattern-determining elements.

A still further object is to provide pattern-controlled lock stops for holding idle carrier bars in the idle position.

Another object is to provide means for driving the carrier bars for yarn-laying movement and auxiliary means for moving selected carrier bars from their idle to selvage position to set them for yarn-laying movement.

Other objects and advantages will be apparent from the accompanying drawings and the following description of a preferred embodiment of the invention.

Referring to the drawings, which show only such portions of a well known straight or full fashioned knitting machine as are sufficient to fully disclose the application thereto of one embodiment of this invention and its manner of operation:

Figure I is a fragmentary front elevational view of the central and left end portions of a conventional knitting machine, parts of the machine unessential to an understanding of this invention being broken away or omitted, and shows the machine provided with a preferred embodiment of the control mechanism of the present invention with the carrier bars in the idle position.

Figure II is an enlarged vertical view, partly in cross section, of the machine, being taken on line II—II of Figure I, and showing mainly the mechanism for selectively driving the carrier bars.

Figure III is a plan view of the top of the machine, being taken on line III—III of Figure I. For the purposes of illustration, parts of the mechanism in this figure have been broken away.

Figure IV is an enlarged vertical cross sectional detail view, being taken on line IV—IV of Figure II and showing a carrier bar in an intermediate operating position.

Figure V (on the last sheet of drawings) is a detail view, with parts broken away, taken on the line V—V in Figure II.

Figure VI is a somewhat diagrammatic rear detail view of the pattern mechanisms shown in the upper right corner of Figure I and is taken on lines VI—VI of Figures II and III, with some of the supporting plates omitted or broken away.

Figure VII is a vertical end view of one of the pattern mechanisms shown in Figure I, being partly in cross section and taken on line VII—VII of that figure.

Figure VIII is a perspective view of the lever 10 shown partially in dotted lines in Figure VI.

Figure IX is an enlarged vertical detail view, being partly in cross section and taken on line IX—IX of Figure III.

Figure X is a top plan view (taken on line X—X 15 of Figure I) of the carrier bars and their stops. For the purposes of illustration, this figure shows both ends of the carrier bars and also all the carrier bars in the selvage position, with intermediate parts of the carrier bars broken away.

Figure XI is a vertical view, partly in cross section and taken substantially on line XI—XI of Figure X. For the purposes of illustration, this figure shows only one carrier bar and only the stops which control this particular carrier bar.

Figure XII is an enlarged vertical cross sectional view taken on line XII—XII of Figure X.

Figures XIII to XV are diagrammatic views showing one end of a carrier bar in three positions of adjustment and also the manner of co-operation between the several automatic stops and the end of the carrier bar.

Figure XVI is an enlarged side view of the auxiliary carrier bar driving means shown in Figure I, being taken on lines XVI—XVI of that figure.

Figure XVII is a rear detail view of the auxiliary carrier bar driving means shown in Figures I and XVI.

Figure XVIII is a perspective view of the operating connections for the auxiliary carrier bar driving means and for the two pattern mechanisms shown in the upper right corner of Figure I, which connections are partially shown in Figures I and II.

Figure XIX is an enlarged top plan view of a detail of Figure XVIII.

Figure XX is a detail side view in elevation of one of the pattern chain blocks for pattern mechanism F shown in Figures I, XVIII and XLIX.

Figure XXI is a detail end view in elevation of one of the pattern chain blocks for pattern mechanism B shown in Figures I, III and VI.

The knitting machine illustrated in the drawings is of the usual multi-section type. Its general construction and operation are well understood and therefore require no particular description other than will appear in connection with that setting forth this invention. In general, this invention provides mechanism for a conventional knitting machine to automatically control the selection and operation of the several conventional carrier bars, which selection and operation, heretofore, have usually been controlled manually.

In straight knitting machines, as is well known, the yarn is fed to the sinkers by yarn carriers (not shown) mounted on longitudinally movable carrier bars 1 which usually extend the length of the machine, and which are arranged in staggered relation when each one is in its idle position. This staggered positioning is the result of the odd-numbered carrier bars 1 (constituting a series) being moved toward one end of the machine to one extreme position of possible move-

ment, and the even-numbered carrier bars 1 (constituting another series) toward the other end of the machine to an extreme position. If an idle carrier bar is to be used in the knitting operation, it is usually shifted manually by the operator from its extreme or idle position to the selvage position so that its yarn carriers are placed at the selvage or edge of the fabric being knit. When the yarn carriers are in the selvage position they are ready to lay their yarn. Motion for the yarn-laying movement is usually imparted to selected carrier bars 1 from a reciprocating rod 2 (see Figures I and II) operated by the usual coupler motion mechanism (not shown). The selection of a desired carrier bar has commonly been determined by manual adjustment of driving connections between the carrier bars 1 and the reciprocating rod 2, the adjustment being effected while the knitting machine is idle for this particular purpose. The present improvements provide driving connections between the carrier bars 1 and the reciprocating rod 2 and also provide automatic control of these driving connections to selectively operate the individual carrier bars.

Drive for carrier bars

The carrier bar drive A (see Figure I), for coupling individual carrier bars 1 to rod 2 is characterized by its compact construction to permit its location at only a single control point or station on the machine. As will be seen, by referring particularly to Figures II, IV and V, the carrier bar drive A of Figure I includes a drum 3 having its axis extending transversely of the carrier bars 1 and keyed to a shaft 4 which is journaled in bearing brackets 5. The drum 3 is oscillated by reciprocating rod 2 through the intermediary of a crank arm 6, a block 7 secured to the arm 6 and adapted to be manually adjusted therewith, a link 8, and a sleeve 9 adjustably secured to rod 2, the link 8 being pivotally connected at its opposite ends to the block 7 and the sleeve 9 respectively.

The carrier bars 1 may be selectively coupled to the oscillating drum 3, so as to be individually driven and longitudinally reciprocated thereby. For this purpose, there is a split clutch or friction band 10 for each carrier bar 1. These bands 10, which may be resilient, encircle the drum 3 and are positioned in grooves in the latter. Upon contraction of any selected band 10, it frictionally engages the drum 3 so as to oscillate (rotate alternately in opposite directions) therewith. The selected band 10, upon being driven, reciprocates its carrier bar 1 by means of an arm 11 projecting from the band 10, a link 12, and a plate 13 secured to the carrier bar 1 (see Figure IV). It is thus readily seen that by determined control of the friction bands 10 by mechanism hereinafter described, selective operation of any one or more carrier bars is readily secured. Links 12 are positioned on the right side of the bands 10 (looking at Figure I) for those carrier bars (1) which move toward the right end of the machine in assuming an idle position, while the links 12 for the other carrier bars (1) are arranged on the left side of their friction bands 10.

The contraction of each friction band 10 is effected by a cam lever 14 pivotally mounted on the end of a pin 15 extending through the bent ends of the band 10 (see Figure IV). A nut 16 on the other end of the pin 15 secures the latter in place and provides for adjustment of the cam lever 14. A spring 17, encircling the pin 15 and positioned between the bent ends of the friction

band 10, opposes the action of the cam lever 14. When a cam lever 14 is free to turn on its pivot, its spring 17 tends to assist the resilient friction band 10 in expanding, so that the friction band 10 will be released from driving engagement with drum 3. Two of the levers 14 in released position are shown in Figure I. On the other hand, when pressure is exerted on the outer end of a lever 14, its inner or cam end engages the face of the adjacent bent end of the friction band 10 and forces the two bent ends together to contract the band 10 about the drum 3 for driving engagement therewith (see Figure IV).

It will be noted that the illustrated carrier bar drive A provides a plurality of clutch means or friction bands 10 between the drum 3 and the carrier bars 1, that is, separate clutch means for each carrier bar 1. These clutch means are positioned at a single control station, since they are all arranged to travel over substantially the same longitudinal portion of the knitting machine as distinguished from the travel of conventional friction boxes such as are shown in the Koeberling et al. Patent 2,062,913, dated December 1, 1936. As illustrated by the Koeberling patent, conventional friction boxes are distributed in widely spaced relation along the length of a friction rod extending the full length of the knitting machine. Such conventional arrangement results in the friction boxes traveling in aligned paths spaced longitudinally of the machine. In the embodiment shown by my accompanying drawings, the clutch means 10 between drum 3 and the carrier bars 1 travel in laterally spaced, parallel paths of movement.

Automatic control of carrier bar drive

As will be seen in Figures I and II, the mechanism for controlling the carrier bar drive A to selectively operate one or more individual carrier bars 1 is also compactly designed to be positioned at the same control point on the machine as the carrier bar drive A just described.

For controlling the cam levers 14 to effect the contraction and release of the clutch or friction bands 10, each cam lever 14 is provided with a race which consists of a set of two arcuate arms 18 extending in opposite directions and pivotally secured at their adjacent inner ends to a shaft 19 (see Figures II, IV and V). Collars 20 (Figure II) mounted on shaft 19 properly space the sets of arms 18 and prevent their shifting on the shaft 19. When a set of arms 18 is swung on the shaft 19 from a raised inoperative position, as shown in Figure I, to a lowered operative position, as shown in Figure IV, the set of arms 18 forms a single arcuate race and operates the cam lever 14 of the friction band 10 immediately below the lowered race-forming arms 18. The arms 18 in being lowered, swing the lever 14 on its pivot to cam the friction band 10 to contracted position. When a friction band 10 is contracted, it will be driven by the drum 3 and transmit this drive to its carrier bar 1. The cam lever 14 of a contracted band 10 moves therewith in the carrier bar driving operation, and such lever 14 is held in operative position by the lowered race with which it is constantly engaged. This constant engagement maintains the friction band 10 in contracted position during movement of the friction band 10 relative to its race. To reduce the friction between a race and its cooperating cam lever 14, the latter may have a roller 21 mounted on its outer or race-engaging end. Raising of the outer ends of a previously lowered set of arms 18

5 effects disengagement between a particular friction band 10 and the drum 3, if the roller 21 co-operating with those arms 18 has reached its limit of movement in either direction. Each roller 21 is preferably positioned diametrically opposite the arm 11 connected to the same friction band 10, so as to be capable of the same extent of movement on both sides of the center of the race (see Figure IV).

10 The desired swinging movement of each set of race arms 18 about the shaft 19 is effected by a pair of links 22 which connect the outer ends of arms 18 to a cross link 23 carried on the lower end of a vertically reciprocable control rod 24. The rods 24 may have threaded engagement with the links 23, and nuts 25 may be provided to lock each rod 24 to its cross link 23. The rods 24 pass through a guide plate 26, which is secured to brackets 5 and limits the upward movement of the rods 24 by engagement with the nuts 25.

15 Springs 27 (Figures I and VI) serve to yieldingly maintain the control rods 24 in their raised or inoperative positions. The lower end of each spring 27 is connected to a finger 28 secured to a control rod 24, while the other end is supported by a fixed bar 29 extending between two stationary frame members 30.

20 Control rods 24 are actuated by pattern mechanism to control the selective operation of individual friction bands 10 and the individual carrier bars 1. For this purpose, the upper end of each of the control rods 24 (see Figure VI) is pivotally secured to a control lever 31 mounted on the shaft 32 extending between frame members 30. Spacing collars 33 (see Figures II and VI), mounted on shaft 32 and between the control levers 31, prevent shifting of the latter on the shaft 32. The pattern mechanism B, about to be described, selectively engages the control levers 31 to swing them on the shaft 32 and lower the respective control rods 24. This pattern mechanism B comprises a sprocket wheel 34 and an idler 35 supporting a pattern chain 36 (see Figures I and VI). The chain 36 carries a longitudinal row of pattern blocks or buttons 37 for each carrier bar 1, and the pattern blocks 37 in each row are spaced along the length of the chain 36 to secure determined operation of the control lever 31 and the carrier bar 1 controlled thereby. As lengthwise movement is imparted to chain 36 in the direction indicated by the arrows in Figures I and VI, the pattern blocks 37 in determined order move over projections 38 carried by levers 31, and in so doing exert cam action against the projections 38 to swing the levers 31 downwardly on the shaft 32 to lower their respective control rods 24 and thereby contract corresponding friction bands 10. The pattern chain 36 is advanced a step at a time, and between advances remains stationary. When pattern chain 36 is in such position that it couples a carrier bar 1 to the driving drum 3, it is at rest and a pattern block 37 remains in engagement with the projection 38 of the control lever 31 for that particular carrier bar 1 to hold the lever 31 in the depressed position. At the time a particular carrier bar 1 is to cease operation, the pattern chain 36 is moved a step to advance the button 37, which has been effecting that operation, beyond the projection 38 on the depressed lever 31, so that the depressed lever 31 may be restored along with its rod 24 to the inoperative position by the corresponding spring 27.

25 The pattern mechanism B is termed a style determining pattern mechanism and is used to

control the carrier bar drive A when each of the selected carrier bars 1 is intended to continue operation for a number of successive courses of loops. In producing stocking fabric or certain portions thereof, it is frequently the practice to operate different carrier bars for successive courses of loops to mix the yarns in the fabric and thereby eliminate shadows and streaks. According to a preferred form of this invention, such operation is controlled by a second pattern mechanism C which may for that reason be termed a yarn mixing pattern mechanism. In the drawings, and particularly in Figures I, VI and VII, pattern mechanism C is shown as being adapted to operate the front three control rods 24 and the corresponding front three carrier bars 1. It is obvious, of course, that pattern mechanism C may be used to control any group or all of the carrier bars 1. It will also be understood that the rods 24 which may be operated by pattern mechanism C may, also, be operated by the pattern mechanism B. Each of the rods 24 operated by pattern mechanism C has an arm 39, which is operated by a control lever 40 mounted on a fixed shaft 41. The control levers 40 are held against shifting movement on the shaft 41 by spacing collars 42 (see Figures VI and VII). The control levers 40 are operated by the pattern mechanism C in the same manner as levers 31 are operated by the so-called style determining pattern mechanism B. The pattern mechanism C comprises a sprocket wheel 43, an idler 44, and a pattern chain 45 carrying three columns or longitudinally extending rows of pattern blocks or buttons 46. Chain 45 may be relatively short in length as it is intended to operate the corresponding carrier bars (1) in repeated sequences with each sequence corresponding to a few courses of loops, though the chain 45 may be relatively longer and the sequences relatively larger. Chain 45 may also be of any desired width in order to control as many operating rods 24 as necessary. The spacing and positioning of pattern blocks 46 determines the order of operation of the levers 40 and their respective rods 24. Pattern blocks 46, accordingly, may be positioned for operating the carrier bars one, two or more at a time. As each pattern block 46 moves to a position over a control lever 40, it has cam engagement with a projection 47 on that lever 40 to swing the latter on the shaft 41 and force an arm 39 and its rod 24 downwardly for contracting a corresponding friction band 10.

Pattern chain 45 may be advanced either one or two steps at a time, and successive pattern blocks 46 are spaced longitudinally of the chain the distance of two steps. The successive pattern blocks 46 are also positioned on the chain 45 in accordance with the desired order of operation of the control levers 40. If a pattern block 46 is in engagement with a projection 47 of a control lever 40, and the chain 45 is advanced only one step, the chain will come to rest in a position in which none of the pattern blocks 46 is opposite a projection 47. In this position of pattern chain 45, the control of the carrier bars 1 by the pattern mechanism C is interrupted. If the pattern mechanism C is to again control the corresponding carrier bars 1, chain 45 is advanced one step to effect engagement between a pattern block 46 and a projection 47. Thereafter or during the control of the carrier bar drive A by pattern mechanism C, the pattern chain 45 is advanced two steps at a time.

As will be seen from Figures I, II, VI and VII, 75

pattern mechanisms B and C are similarly supported on the machine, are operated by similar pawl and ratchet drives, and are provided with similar friction disks for limiting their movement. 5 A description of these features in connection with one pattern mechanism is, therefore, sufficient for a complete understanding of these features in connection with both of the pattern mechanisms B and C. The sprocket wheel 34 of 10 pattern mechanism B is keyed to a shaft 48 which is rotatably supported in two plates 49 mounted on frame members 30. One end of the shaft 48 has threaded engagement with a friction disk 50 (see Figures I and II) which is locked 15 on the shaft 48 by a lock nut 51 in such position that it frictionally engages the adjacent supporting plate 49 to maintain the sprocket wheel 34 in any adjusted position and to prevent movement of the sprocket wheel 34 in excess of that desired when it is advanced to bring the pattern blocks 37 to operative positions. The other end of shaft 48 is keyed to a driving ratchet 52 (see Figures II and VI) which is operated by a spring-pressed pawl 53 carried by the lever 54 rotatably supported at one end by shaft 48 so as to have pivotal movement about the same. Lever 54 is pivotally connected at its other end to a connecting rod 55. Connecting rod 56 is similar in function to connecting rod 55 and operates the pawl 30 and ratchet drive of the sprocket wheel 43 of pattern mechanism C.

As the two pattern mechanisms B and C are mounted over and adjacent the carrier bar drive A, they are positioned at the same control station as the latter. Reference to Figure I also shows that the pattern mechanisms B and C are arranged on the knitting machine and substantially within the longitudinal portion thereof defined by the end limits of travel of the carrier bar drive A. An attendant stationed at the front or rear of the carrier bar drive A will, therefore, be in a position to inspect, and if necessary repair or adjust, the pattern mechanisms B and C. Such arrangement will eliminate the loss of time which would otherwise be occasioned by the attendant walking along the machine from one mechanism to another in his inspection, adjustment and repair of carrier bar operating means.

Carrier bar stops

This invention also provides a shiftable control unit D (see Figures I and X) at each end of the machine, each unit D having stops for controlling the operation of the carrier bars 1. These 55 stops and their manner of operation are shown in Figures X to XV. For the purposes of illustration, Figure XI shows a single carrier bar 1 and only the stops that control that particular carrier bar, it being understood that a similar arrangement of stops is provided for each of the other carrier bars (1) of the machine (see Figure X). As shown in Figure XI, four stops are provided for the carrier bar (1). These are: an automatically controlled end stop 70, a manually controlled end stop 71, an automatically controlled lock stop 72, and an arresting lever or selavage stop 73. For cooperation with the lock and selavage stops (72 and 73), each carrier bar 1 carries a fixed dog 74 provided with an inclined upper cam surface. Each end of a carrier bar 1 carries a bifurcated member 75 supporting an adjustable screw 76 which is adapted to strike a lowered end stop (70 or 71) to limit the movement of the carrier bar.

In view of the previously described, conven-

tional practice of staggering the carrier bars when idle, the automatically controlled stops 70, 72, 73 of a particular carrier bar are preferably arranged at the end of the machine toward which that carrier bar (1) moves in assuming its idle position.

For the purposes of illustration, Figure X shows the relative arrangement of the two series of carrier bars 1 if all the latter were moved to their selvage positions from their idle positions. The carrier bars 1 (as shown in Figure X) are still staggered and each carrier bar 1 is now ready to begin its yarn laying movement. Figure X also shows the automatically controlled stops 70, 72, 73 and dogs 74 at the left end of the machine for controlling the series of carrier bars 1 which assume an extreme position toward the left end of the machine when idle, and similar stops 70, 72, 73 and dogs 74 at the other end of the machine for the other series of carrier bars 1. Figure X shows further that the manually controlled stop 71 for each carrier bar is at the end of the machine opposite to the one having the automatic stops 70, 72, 73 for that same carrier bar.

In practicing a preferred embodiment of this invention, each carrier bar is provided with separate stops 70, 71, 72, but only one arresting lever 73 is provided for each of the two series of carrier bars (1).

All the carrier bars are controlled in the same manner by their respective stops 70, 71, 72 and 73. The order of operation of the stops for a single carrier bar, as illustrated in Figures XIII to XV, is as follows:

Figure XIII shows a carrier bar (1) in its idle or inoperative position and a lock stop 72 engaging the dog 74 to prevent accidental movement of the carrier bar (1) toward the right and away from such position, the end stop 70 and selvage stop or arresting lever 73 resting on top of the carrier bar.

When the carrier bar 1 is to be used in laying yarn, its lock stop 72 is raised. The carrier bar 1 is now free to move, and an auxiliary friction drive (described hereinafter) effects movement of the released carrier bar (1) from idle to selvage position. The arresting lever 73, by engaging the dog 74 (see Figure XIV) serves to stop the carrier bar in the selvage position. The end stop 70 now drops behind the end of the carrier bar 1 (see Figure XIV).

Any carrier bar 1 in the selvage position, which is illustrated by the carrier bars in Figures X, XI and XIV, is ready to begin its yarn laying movement. At the proper time, the arresting lever or selvage stop 73 is raised (see Figure XV) clear of the dog 74 to free the carrier bar 1 in the selvage position so that it may be operated by the carrier bar drive A previously described.

The operating carrier bar 1 reciprocates to lay the yarn and at the opposite limits of such movement, it is arrested by its end stops 70 and 71, which now are in the positions shown in Figure XI. Each of the stops 70 and 71 by arresting the carrier bar 1 causes the friction band 10 for that carrier bar to slip on drum 3, until movement of the drum 3 is reversed. As a carrier bar 1 returns to strike its end stop 70, its dog 74 due to its inclined upper cam surface lifts and passes under its arresting lever 73 and the latter drops behind dog 74 to the position shown in Figure XIV. When the motion of the carrier bar 1 is to be reversed, the arresting lever 73 is again raised to release the carrier bar.

If the reciprocating carrier bar 1 is to have its

operation discontinued, its end stop 70 is raised to permit it to move to the idle position where it will be held by its lock stop 72 (see Figure XIII). As a carrier bar advances to its idle position, the carrier bar dog 74 due to its inclined upper cam surface raises the lock stop 72 and passes under and beyond same. Each carrier bar is stopped, as it arrives at its idle position, in conventional manner by the engagement of the usual yarn carrier holders (not shown), which it carries, with the usual stationary carrier bar guide brackets 11 shown in Figures I and X.

Supports and operating mechanism for carrier bar stops

The shiftable control units D include the usual narrowing heads 80 which in the practice of this invention, are operated or shifted in conventional manner and by conventional mechanism (not shown) to vary the length of the yarn laying stroke of the carrier bars 1. The two units D and their narrowing heads 80 provide similar guides and supports for their stops 70 to 73.

Each narrowing head 80 carries a grooved plate 81 for guiding the carrier bars 1, and each plate 81 in turn carries a guide bracket 82 slotted to receive a selvage stop lever 73 (see Figures XI and XII). Each selvage stop lever 73 is slidably and pivotally mounted on a rod 83 so as to be free to rise and fall in the slot of bracket 82 and to be free to be shifted along the rod 83 by the bracket 82 in the usual narrowing motion of its narrowing head 80.

Each selvage stop lever 73 may be actuated by means similar to that employed in operating the well-known plating stop or arresting levers of conventional machines. This means consists of an operating arm 84 projecting from the pivotally mounted end of arm 73, and a cam 85 carried by a cam bar 86 (transverse cross section shown in Figure XII). Cam bar 86 is longitudinally reciprocated by conventional mechanism (not shown), and its operation is so timed that a cam 85 rocks an arm 84 to raise its lever 73 at the instant the carrier bar or bars 1 controlled or held thereby are to begin their yarn laying stroke.

Each narrowing head 80 carries two pairs of guide bars 87, 88 for slidably receiving the corresponding stops 70, 71 and 72 (see Figures X and XI). Spacing blocks 89 and 90 carried between the guide bars 87 and 88 maintain the stops 70, 71 and 72 in alignment with their respective carrier bars 1. Each narrowing head 80 has a block 91 to provide a bottom rest for its stops 70 and 71 when they are in their lower-most position. The housings for the stops 70, 71 and 72 are supported by the narrowing heads 80, and each housing comprises a top 93 and side walls 92, to which are suitably secured the ends of guide bars 87 and 88.

All of the stops 70 and 72 shown in Figure X are operated through the intermediary of similar connections by the pattern mechanism B. Referring to Figure XI, each of the stops 70, 72 is secured to the lower end of an operating flexible cable 100 by means of a set screw 101. A pull on the upper end of a cable 100 is effective to raise its stop (70 or 72). When this lifting force on a cable 100 is removed, its stop is lowered by a spring 102 (Figure XI) connected at its opposite ends to the set screw 101 of the stop and one of the guide bars (87 or 88) for that stop. As shown in Figure IX, each cable 100 has its upper end connected to one arm of a bell crank lever 103 pivotally mounted on a shaft 104 extending

between frame members 30. Intermediate its ends, each cable 100 may be enclosed in a flexible conduit 105, which protects the cable 100 and at the same time permits its operation. This conduit 105 may be of any suitable construction; for example, it might be formed of a helically coiled wire as shown in the drawings. Figures I and XI show a group of conduits 105 at the left end of the knitting machine, and it will be understood that a similar group of conduits 105 is similarly arranged and supported at the other end of the machine. The upper and lower ends of each of the conduits 105 are connected respectively to a fixed bracket 106 (see Figure IX) and the housing top 93 (see Figure XI) by means of set screws 107.

Due to the flexibility of the cables 100 and their protecting conduits 105, the operation of the stops 70 and 72 is unaffected as the narrowing heads 88 are shifted along the machine and have relative movement with regard to the support for the upper ends of the cables 100 and their conduits 105.

Each bell crank lever 103 at the left end of the machine (Figure I), is operated by a rod 108, mounted in guide brackets 109 supported on frame members 30.

In illustrating the previously described operating connections for stops 70 and 72, the drawings (for example, Figures I, III and XI) show completely only those connections for the stops at the left end of the machine. It will be understood, however, that similar operating connections are provided for the stops 70 and 72 at the right end of the machine, which connections include operating rods 110 (shown partially in Figures I, III and VI) similar in character and function to rods 108.

The operating rods 108 and 110 are grouped in pairs as shown in Figures II and III, so that there is a pair of rods (108 or 110) for each of the carrier bars 1. The two operating rods in each pair may be considered as left and right rods respectively (looking at Figures II and III), and the rod on the right in each pair controls the lock stop 72 and the rod on the left controls the end stop 70 of a particular carrier bar. Each of the so-called "right" rods 108 is operated by a control lever 111-b, each "left" rod 108 by a control lever 111-a, each "right" rod 110 by a control lever 112-b, and each "left" rod 110 by a control lever 112-a. The control levers (111-a, 111-b, 112-a, and 112-b) are arranged in sets of two, similarly to the rods (108 or 110) they operate, so that in each set of control levers for rods 108, there will be a lock stop control lever 111-b and an end stop control lever 111-a, and in each set of control levers for rods 110, there will be a lock stop control lever 112-b and an end stop control lever 112-a.

Each of the control levers 111-a, 111-b, 112-a, and 112-b is pivotally mounted on a shaft 113 secured at its ends to supporting plates 48, and these control levers are spaced in pairs and prevented from shifting along shaft 113 by spacing collars 113-a encircling the shaft 113. The control levers 112-a and 112-b have their upper ends extending above the pattern mechanism B so that they may be connected to their respective rods 110.

It will now be understood that there is a pair of control levers (111-a and 111-b or 112-a and 112-b) and a control lever 31 for each carrier bar 1. These three control levers for each carrier bar are so positioned as to be controlled

by a single column or longitudinal row of pattern blocks or buttons 37, there being as many rows of pattern blocks 37 as there are carrier bars 1. In operating the levers 111-a, 111-b, 112-a and 112-b, the blocks 37 engage their lower ends, as may be seen from Figure VI.

The pattern chain 36 is advanced step by step in the direction indicated by the arrow in Figure VI so that the pattern blocks 37 in each row first pass their control levers (111-a and 111-b or 112-a and 112-b) and then their friction band control lever 31.

As shown in Figure XXI, each of the blocks 37 has an upper part cut away so as to provide a projection 114 on only one side of its top. The positioning of a pattern block 37 with its projection 114 on its right or left side with regard to its direction of movement determines whether that pattern block 37 will operate an end stop control lever (111-a or 112-a) or a lock stop control lever (111-b or 112-b) as shown by Figures II and III. Control levers 31 are so positioned, or their projections 38 are so arranged, that they are operated by the same pattern blocks 37 (or projections 114) that operate the lock stop control levers (111-b or 112-b). The pattern blocks 37 that operate the end stop control levers (111-a or 112-a) do not engage the projections on the control levers 31, but pass along one side thereof.

Each of the bell crank levers 103 is connected to one end of a spring 115 (see Figures I and IX), the other end being secured to a stationary bar 116. The springs 115 serve a two-fold purpose: first, they yieldingly act on the bell crank levers 103 to maintain the control levers (111-a, 111-b, 112-a and 112-b) in position to be operated by the pattern blocks 37 at the desired times; second, they assist the springs 102 (Figure XI) in automatically lowering the stops 70 and 72 when the corresponding control levers (111-a, 111-b, 112-a, and 112-b) are released by their pattern blocks 37.

Frame members 30, already referred to, are added to the conventional machine frame and extend substantially the entire length of the machine. These frame members 30 may be suitably supported above the machine by upright frame members 116 mounted on available parts (not shown) of the usual machine frame.

Auxiliary drive for carrier bars

According to this invention, a separate or auxiliary carrier bar drive E (Figure I) is provided to move released carrier bars 1 from their idle position (see Figures I and XIII) to their selavage position (see Figures X, XI and XIV). This auxiliary driving mechanism, which is shown in detail in Figures XVI and XVII, comprises a pair of drums 120 each keyed to a shaft 121 rotatably mounted in two bearing brackets 122. Each drum 120 is encircled by a set of three clutch or friction bands 123, so that there is a total of six friction bands 123, or one for each carrier bar 1 of the machine. Each friction band 123 is intended to drive its carrier bar in only one direction. This drive is obtained by an operating arm 124 projecting from each friction band 123 for engagement with a dog 125 secured to a carrier bar (1).

One of the drums 120 (the one on the left in Figure I) and its friction bands 123 provide the desired auxiliary one-way drive for the set of three carrier bars which, when idle, assume an extreme right position (looking at Fig. I) with

respect to the machine; while the other drum 120 and its friction bands 123 provide the drive for the other set of three carrier bars which, when idle, assume an extreme left position. As the two sets of carrier bars 1 (previously referred to) move in opposite directions in passing from their idle to selvage positions, the drums 120 are rotated in opposite directions in their driving stroke as shown by the arrows in Figure XVII, so that their friction bands 123 will move in the proper direction to move any released carrier bar (1) from idle to selvage positions.

As shown particularly in Figures I and XVII, when all of the carrier bars 1 are in the idle position, the dogs 125 abut the operating arms 124, and the latter are aligned against stationary stop bars 126 secured to brackets 122. It will thus be seen that each arm 124 in its idle position (see Figure XVII) is restrained from moving in one direction by a stop bar 126, and in the other by a dog 125, which is in turn held against movement as long as its carrier bar 1 is held by a lock stop 72 (see Figure XIII). When a lock stop 72 is raised in the manner already described, its carrier bar 1 is released, and the operating arm 124 for the released carrier bar 1 moves in the direction toward the dog 125 of that carrier bar and thereby moves the released carrier bar to its selvage position where it is arrested by a selvage stop lever 73 (see Figure XIV).

The drive from each drum 120 to its bands 123 is frictional, so that when the drums 120 are oscillated, the friction bands 123 of the carrier bars 1, which are held by lock stops 72 will slip on their drums 120. Each friction band 123 is also adapted to slip on its drum 120 when the friction band (123) towards the end of its driving stroke has its carrier bar (1) stopped by a selvage stop 73 and to slip at the end of its return stroke when its arm 124 strikes its stop bar 126. The friction bands 123 are contracted to frictionally grip their drums 120 by means of bolts 127 and nuts 128 connecting the two ends of each of the friction bands 123. The degree of frictional engagement between a friction band 123 and its drum 120 may be varied by adjusting the nut 128 for that band. Collars 129 secured to each of the drum shafts 121 prevent axial shifting of both the drums 120 and their shafts 121.

Shafts 121 are oscillated simultaneously in reverse directions by means of levers 130 and links 131 which connect the levers 130 to the upper end of a connecting rod 132 in the manner clearly illustrated in Figures XVI and XVII.

Cam-controlled operation of pattern mechanisms B and C and auxiliary carrier bar drive

Timed operation of the connecting rods 55, 56 and 132 is provided by the mechanism shown particularly in Figure XVIII. The connecting rods 55 and 56 are operatively connected to the ends of similar cam levers 140 and 141 respectively. These levers 140 and 141 are pivotally supported by similar stationary bearing brackets 142 and 143 respectively. The cam levers 140 and 141 are individually controlled by catch levers 144 and 145 respectively, which normally engage the cam levers 140 and 141, as shown in Figures I and XVIII, to maintain them in the raised or inoperative position. When cam levers 140 and 141 are released by their catch levers 144 and 145, they are individually controlled by cooperation of the rollers 146 and 147, which they carry, with the cams 148 and 149 secured to the cam shaft 150. Cams 148 and 149 are in the form of round

disks having a part removed to provide a flat or straight cam surface on one side (see Figures II and XVIII). Catch levers 144 and 145 normally hold their respective cam levers 140 and 141 in such position that the rollers 146 and 147 contact only the circular portion of the periphery of the cams 148 and 149 as the latter rotate with the cam shaft 150.

The connecting rod 55 is intended to have the same extent of movement every time it is actuated. Catch lever 144, therefore, whenever shifted to the right (looking at Figures I or XVIII) permits roller 146 to remain in contact with the peripheral cam surface of cam 148 while the flat or straight cam portion of the latter is passing the roller 146. To insure constant engagement between the roller 146 and its cam 148 during release of the cam lever 140, the latter is provided with a spring 151. This spring 151 is connected at one end to cam lever 140 and at its other end to the stationary bar 152, so that it constantly tends to swing the cam lever 140 towards its actuating cam 148.

The connecting rod 56, however, is intended to have either of two movements depending on whether the pattern chain 45, which it drives, is to be advanced one or two steps for the purpose already described. Cam lever 141, therefore, is so controlled as to have two possible movements of different extent. Such control is secured by the stepped shoulders 153 and 154 (see Figures I and XVIII) on catch lever 145. In the normal position of catch lever 145, already referred to, the end of cam lever 141 rests on shoulder 153. A spring 155, anchored to stationary rod 152 and secured to one end of cam lever 141, always tends to hold the roller 147 against the periphery of cam 149. When catch lever 145 is shifted to the right (looking at Figures I or XVIII) to bring shoulder 154 under the end of lever 141, the shoulder (154) will limit the extent of downward movement of the catch-controlled end of lever 141 as the straight cam surface of cam 149 passes the roller 147. If catch lever 145 is shifted to the right so that neither of the shoulders (153 or 154) is beneath the end of cam lever 141, the latter will have a full movement as the straight cam surface of cam 149 passes roller 147. It will thus be seen that when shoulder 154 is under the end of lever 141, the pattern chain 45 will be advanced one step in a revolution of cam 149 and that when catch lever 145 is shifted to entirely free cam lever 141, the pattern chain 45 will be advanced the distance of two steps.

To yieldingly maintain the catch lever 145 in its three positions of adjustment, its upper end is provided with suitable notches 156 engaged by a spring actuated pawl 157 mounted on a stationary part of the machine. These notches 156 and pawl 157, however, permit ready operation of the lever 145 by the means described hereinafter.

After the straight cam surface of either cam 148 or 149 passes its roller (146 or 147), the round cam surface of the cam holds the roller and its cam lever (140 or 141) in such position that the cam lever (140 or 141) will be reengaged and held against operation by its catch lever (144 or 145) when the latter is restored to normal position. To permit the desired swinging movement of catch levers 144 and 145, they are pivotally mounted on stationary shafts 158 and 159 respectively.

Catch lever 144 is determinedly operated by a control rod 160 connected to a two-arm control

lever 161 pivotally mounted on the stationary shaft 162. The control lever 161 is held in normal position by a spring 163 which is connected to the lever 161 so that the catch lever 144 is yieldingly maintained under its cam lever 140. Operation of lever 161 is provided by pattern mechanism (described hereinafter) which opposes the action of spring 163.

Catch lever 145 is determinedly operated by a control rod 164 connected to a three-arm control lever 165 pivotally mounted on shaft 162. Control lever 165 has two operating arms 166 and 167 which are pattern controlled (as explained hereinafter) to rock catch lever 145 in reverse directions. Arm 167 is offset, so that it is laterally displaced with respect to arm 166 and the two arms may be selectively operated as will appear more clearly hereinafter.

Control lever 161 also controls the operations of connecting rod 132. The latter is operatively connected to a cam lever 168 mounted on a stationary bracket 169. The cam lever 168 carries a roller 170 which normally rides on the periphery of a circular disk 171 fixed to cam shaft 150. A spring 172, connected to both stationary bar 152 and cam lever 168, holds the latter in its normal position against stop 169a. Roller 170 is shiftable axially (see Figures I and XVIII) on the forked end of cam lever 168 so that it may be positioned in the path of a cam piece 173 carried on the side of disk 171. Shifting of roller 170 is effected by a forked rocker arm 174 secured to the rock shaft 175 which is operatively connected to control lever 161 by rocker arm 176 and link 177. The flat cam surfaces of cams 148 and 149 have the same relative position with respect to cam shaft 150 so that they pass their rollers (146 and 147) at the same time, while cam piece 173 is so positioned as to engage roller 170 (when shifted) just after rollers 146 and 147 come opposite the straight cam portions of cams 148 and 149. The cam shaft 150 makes one revolution in each operation of the machine and is so timed that the flat portions of cams 148 and 149 and the cam piece 173 pass their respective rollers (146, 147, and 170) between operations of the carrier bars 1.

Main or master control pattern mechanism

The desired timed operation of all the foregoing mechanisms is controlled and secured by the main or master control pattern mechanism shown at F in Figure I and in detail in Figures XVIII and XIX. This main or master control pattern mechanism F comprises a sprocket wheel 180 and an idler 181 supporting a pattern chain 182 provided with pattern blocks or buttons 183, 184 and 185.

The conventional full-fashioned straight knitting machine of today has a so-called "chain motion" for automatically controlling the movement of the narrowing heads 80, the usual loose course motion (not shown), and the conventional reinforced selavage attachment (not shown). According to this invention, the pattern chain of the conventional "chain motion" is widened to accommodate additional pattern blocks or buttons for controlling the various parts of the present improvement. This widened chain is the chain 182 in the drawings, and the additional pattern blocks are blocks 183, 184 and 185 in the drawings. Chain 182 is driven in the direction indicated by the arrow in Figure I by the usual driving mechanism (not shown) of the conventional "chain motion" previously referred to.

This conventional drive imparts step by step motion to the chain 182, so that the chain advances one step between successive operations of the machine and idles during each operation of the machine.

Pattern blocks 183, 184 and 185 may be positioned on the pattern chain 182 in accordance with any order of operation that is desired for the various mechanisms of this invention which have already been described. As the chain 182 is advanced, the pattern blocks 183, which are arranged in a row extending longitudinally of the chain 182, have cam engagement with the lower end of control lever 161 and swing the latter against the action of spring 163 to shift catch lever 144 and roller 170 for the purposes described. The pattern blocks 183 are so arranged on the chain 182 that each pattern block 183 in actuating lever 161 remains in the actuating position while the chain 182 is idling prior to its next advance.

One or more pattern blocks 185 are arranged on the chain 182 to actuate lever arm 166 clockwise, and one or more pattern blocks 184 are arranged to operate lever arm 167 counterclockwise. Pattern blocks 184 and 185 are identical and have the shape shown in Figure XX to provide high and low cam portions 186 and 187. These high and low cam portions, 186 and 187, in operating either of the arms 166 and 167 of lever 165 shift the operated arm to different extents. Each pattern block (184 or 185) is placed on the chain 182 so that the low cam portion 187 leads. In general, the pattern chain 182 will be provided with only one pattern block 184 and with only one pattern block 185, though obviously more may be used when necessary.

The pattern block 185 is effective to initiate the operation of pattern mechanism C and is, therefore, placed on pattern chain 182 in advance of pattern block 184. In one of the movements of pattern chain 182, the low cam portion 187 of pattern block 185 is brought into engagement with lever arm 166 to move it clockwise for a short distance, so that catch lever 145 has its shoulder 154 brought under the end of cam lever 141. This engagement between cam portion 187 and lever arm 166 is maintained during the subsequent idle period of pattern chain 182. In the next or succeeding advance of pattern chain 182, cam portion 187 is moved away from engagement and cam portion 186 into engagement with lever arm 166. The higher cam portion 186 provides an additional clockwise movement of lever arm 166 so that the catch lever 145 frees cam lever 141 for full movement. Lever arm 166 and catch lever 145 are left in this second set position as long as it is desired that pattern mechanism C should operate, and this setting is not changed as the high cam portion 186 passes beyond lever arm 166. In each of its set positions, catch lever 145 is yieldingly held against accidental movement by the previously described spring actuated pawl 157.

Pattern block 184 is effective to discontinue the operation of pattern mechanism C, and is positioned at any desired point on chain 182—generally far behind the pattern block 185. It will, therefore, be understood that the close positioning of the pattern blocks 184 and 185 in Figures XVIII and XIX is chosen merely for illustration purposes. The pattern block 184 is carried by the chain 182 for engagement with lever arm 167 in the same way that pattern block 185 engages lever arm 166. The low cam portion 187 of pattern

block 184 is the first to engage lever 167 and moves the latter counterclockwise to such an extent that shoulder 154 of catch lever 145 is positioned below the end of cam lever 141 while the latter is being held in raised position by the roller 147 riding on the circular portion of cam 149. Cam 149 during its next revolution by its co-operating action with roller 147 provides for an advance of one step of the pattern chain 45 so that the latter will be rendered inoperative. In the next advance of chain 182, the high cam portion 186 of pattern block 184 moves lever arm 167 counterclockwise a further distance to bring shoulder 153 of catch lever 145 under the end of cam lever 141 which is at this time in raised position as the roller 147 is riding on the circular portion of cam 149. The cam lever 141 and the pattern chain 145 are left in this set, inoperative position until lever arm 166 is again operated by a pattern block 185.

Summary of general operation

In the general operation of this invention, the master control pattern mechanism F controls the operation of the style determining pattern mechanism B, the so-called yarn-mixing pattern mechanism C and the auxiliary carrier bar drive E. Pattern mechanism B in turn controls the end and lock stops 70 and 72 of units D as well as the carrier bar drive A. Pattern mechanism C also controls part of carrier bar drive A for selectively operating certain carrier bars 1 while the control of carrier bar drive A by pattern mechanism B is interrupted. The master control pattern mechanism F is advanced once for every operation of the machine, but pattern mechanisms B and C and the auxiliary carrier bar drive E are operated only when carrier bar changes are desired.

When the yarn-mixing pattern mechanism C is idle, the selective control and operation of all the individual carrier bars 1 are the same, and a general explanation with regard to one carrier bar (1) will, therefore, suffice for all.

When a particular carrier bar (1) is to be set for operation, the pattern chain 182 of pattern mechanism F brings a pattern block 183 into engagement with lever 161 (Figures I, XVIII and XIX). As a result, lever 161 is actuated so that chain 36 of pattern mechanism B may be advanced one step and through the intermediary of one of its pattern blocks 37 (see Figure III) operate a lock stop control lever (111-b or 112-b) to effect the raising of the lock stop 72 (Figure XI) for the selected carrier bar 1. Actuation of the lever 161 (Figure I) also provides for operation of the auxiliary carrier bar drive E so that the released carrier bar 1 will be moved from its idle position (Figure XIII) to its selvage position (Figure XIV).

In the next advance of pattern chain 182 (Figures I, XVIII and XIX), another pattern block 183 thereon engages and rocks lever 161 a second time to provide for a further advance of the chain 36 of pattern mechanism B. The pattern block 37, which previously effected the raising of a lock stop 72, in this advance of chain 36, is moved past its lock stop control lever (111-b or 112-b) and into engagement with a lever 31 (Figure IV) to provide for contraction of the friction band 10 (Figures I and IV) which is to drive the chosen carrier bar 1. At the same time, the selvage lever 73 (Figure XI) holding the selected carrier bar 1 is raised to free same for yarn laying movement. Carrier bar drive A

(Figure I) now reciprocates the free carrier bar 1 for yarn laying operation. At the limits of its movement during such operation, the carrier bar 1 is arrested by end stops 70 and 71 now in the positions shown in Figure XI.

Each time that the carrier bar 1 is stopped by its end stop 70, the selvage lever 73 slips behind dog 74 (Figures XI and XIV) to hold the carrier bar 1 against accidental return movement. Lever 73 is again raised when the carrier bar 1 is to begin its return movement.

In order to terminate the operation of a reciprocating carrier bar 1, the master control pattern mechanism F provides a further advance 15 of the chain 36 of pattern mechanism B so that another pattern block 37 will be positioned to engage an end stop control lever (111-a or 112-a) and effect the raising of the end stop 70 for that carrier bar. In the next movement 20 of the carrier bar 1 toward its end stop 70, the carrier bar passes under the end stop 70 and to its idle position where it is held by its lock stop 72 (Figure XIII).

Pattern mechanism B controls the lock stops 72 25 for releasing the individual carrier bars 1, when the carrier bar drive A is under the control of the pattern mechanism B. The latter also provides for the release of the front three carrier bars 1, when these three front carriers 1 are to be placed under control of the yarn-mixing pattern mechanism C. The carrier bars 1, which are released for operation under the control of pattern mechanism C, are moved to their selvage positions by auxiliary carrier bar drive E in the described manner.

As the pattern blocks 37 of pattern mechanism B which unlock the carrier bars 1 for operation under the control of pattern mechanism C also control their friction drive, these particular 30 pattern blocks 37 are so arranged on the chain 36 that after unlocking the front three carrier bars of the machine, they will operate their levers 31 in the same order and at the same time that the corresponding levers 40 are operated by pattern mechanism C. With this arrangement of the pattern blocks 37, pattern mechanism B will not interfere with the desired control of the carrier bar drive A by pattern mechanism C as the pattern mechanism B is being advanced to a position in which all of its pattern blocks 37 are inoperative. The pattern mechanism F by shifting catch lever 145 (Figures I and XVIII) in the manner already described permits the pattern mechanism C to be automatically set for operation and then provides for its repeated operation as and after pattern mechanism B is advanced to an idle, inoperative position.

When pattern mechanism C is to cease operation, pattern mechanism B is advanced to effect 40 raising of the end stops 70 of the operating carrier bars 1, so that the latter may pass to their idle positions and be locked by lock stops 72.

In discontinuing its operation, the chain 45 45 of pattern mechanism C is advanced one step under the control of pattern mechanism F so that it will be left in an idle position in which none of its pattern blocks 46 is in engagement with a lever 40.

The present disclosure is made with reference 50 to a knitting machine having six carrier bars (1), but it is apparent that the invention may be practiced with a machine having any other number of carrier bars.

The foregoing description and the appended drawings are only illustrative of how this inven-

tion may be suitably practiced, and other forms and modifications of this invention may be readily devised within the spirit and scope of the invention, as defined in the following claims.

What I claim is:

1. A mechanism for operating and controlling a plurality of reciprocable yarn carrier supporting means in a straight knitting machine, said mechanism comprising at least two independent, rotary, friction clutch means adapted to provide independent impositive operation for a corresponding number of individual yarn carrier supporting means, said rotary clutch means having their axes of rotation in substantially the same vertical plane, and pattern mechanism for controlling said clutch means to provide operation of said yarn carrier supporting means in a predetermined order.

2. A mechanism for operating and controlling a plurality of reciprocable yarn carrier supporting means in a multi-section, full fashioned hosiery, straight knitting machine, said mechanism comprising an oscillatable driving means, a plurality of rotary friction clutch means adapted to be selectively connected to said driving means in driving relation and to provide independent, impositive, reciprocable operation for the individual yarn carrier supporting means, said plurality of friction clutch means having paths of operation all within substantially the longitudinal portion of the knitting machine in which any one of said plurality of means travels, whereby said plurality of means in use are concentrated at a single control station, separate control means associated with each of said plurality of means to provide for connection and disconnection in the drive between the corresponding carrier supporting means and said driving means, and pattern means for automatically and selectively operating said control means to secure operation of said yarn carrier supporting means in a predetermined order.

3. A mechanism for operating and controlling a plurality of reciprocable yarn carrier supporting means in a multi-section, full fashioned hosiery, straight knitting machine, said mechanism comprising oscillating driving means, a plurality of substantially axially aligned, oscillating devices adapted to be selectively driven by said driving means and to provide independent, impositive, reciprocable operation for the individual yarn carrier supporting means, each of said devices including a friction clutch, and said plurality of devices having paths of operation disposed in laterally spaced, parallel planes, separate control means for each of said devices to control the drive thereof by said driving means, and pattern means for automatically and selectively operating said control means to secure operation of the yarn carrier supporting means in a predetermined order.

4. A mechanism as recited in claim 3 wherein the pattern means is arranged substantially within the longitudinal section of the knitting machine defined by the limits of travel of said devices.

5. A mechanism for operating and controlling a plurality of reciprocable yarn carrier supporting means in a straight knitting machine, said mechanism comprising a plurality of substantially axially aligned rotary clutch devices, means for driving said clutch devices, means for connecting the individual clutch devices to individual yarn carrier supporting means in driving relation, means for each of said clutch devices to control

the operative engagement thereof with said driving means, and pattern means for automatically and selectively operating said control means to secure operation of the yarn carrier supporting means in a predetermined order.

6. In an automatic control mechanism for the movable yarn carrier bars of a straight knitting machine, the combination comprising a rotary driving device to extend transversely of said carrier bars, rotary clutch bands mounted on said device, each band being adapted to be connected to a separate carrier bar for driving the same, and pattern determining means to effect the selective engagement in driving relation of said clutch bands and rotary device and thereby provide for operation of said carrier bars in predetermined order.

10 7. In a multi-section straight knitting machine, the improvement comprising a plurality of movable yarn carrier bars, driving means including a rotary member, a rotary clutch band operatively connected to each of said carrier bars, said clutch bands being positioned at a single control station on the machine for selectively engaging said rotary member in a driving relation to operate the individual carrier bars, and pattern mechanism for controlling said rotary clutch bands to effect the selective engagement thereof with said rotary member and the operation of said carrier bars in a predetermined order.

20 8. In an automatic control mechanism for a straight knitting machine having longitudinally movable yarn carrier supporting elements, the combination comprising a rotary driving member, 25 a plurality of rotary clutch bands for selectively engaging said driving member in driving relation, a series of control members for effecting selective driving engagement between said clutch bands and said driving member, and a pattern mechanism for controlling the operation of said control members.

30 9. An automatic control mechanism for a plurality of movable yarn carrier bars or yarn carrier supporting members in a straight knitting machine, said mechanism comprising a rotary member, a plurality of independent, radially contractible clutch means adapted to be individually adjusted to effect their driving engagement with and disengagement from said rotary member, 35 each of said clutch means being adapted to drive a corresponding one of said carrier bars, and pattern control means operable between strokes of said carrier bars to adjust said clutch means selectively and automatically in predetermined order to operate said carrier bars in corresponding order.

40 10. For use in straight knitting machines of the type adapted to knit hosiery and having a plurality of reciprocable yarn carrier supporting elements, the combination comprising a rotary driving member, a plurality of friction clutch devices for selectively engaging said member to provide selective operation of a corresponding number of the yarn carrier supporting elements, each 45 of said elements to be reciprocated by means of an individual friction clutch device, a separate means for each of said devices to control the operation thereof by said driving member, and means for operating said control means in repeated predetermined sequences to effect yarn laying movement of said yarn carrier supporting elements in rotation to mix the yarns in the hosiery.

50 11. In a multi-section straight knitting machine, the combination comprising a plurality of 55

60

movable yarn carrier bars, means for operating said carrier bars, means for selectively connecting said operating means to the individual carrier bars, two separate pattern mechanisms, and means operable by either of said pattern mechanisms for controlling said connecting means, all of said means and mechanisms being positioned at a single control station on the machine.

12. In a multi-section straight knitting machine, the improvement comprising a plurality of movable yarn carrier bars, means for operating said carrier bars, means positioned at a single control station on the machine for selectively connecting said operating means to the individual carrier bars, two separate pattern mechanisms at said control station, means operable by either of said pattern mechanisms for controlling said connecting means, and automatic means for selectively operating said pattern mechanisms.

13. In an automatic control mechanism for the movable yarn carrier bars of a straight knitting machine, the combination comprising means for operating said carrier bars, means for selectively connecting the individual carrier bars to said operating means, said connecting means having laterally spaced, parallel paths of travel, two separate pattern mechanisms arranged on said machine and within substantially the end limits of said paths of travel, means operable by either pattern mechanism for controlling said connecting means, and automatic means for selectively operating said pattern mechanisms.

14. In an automatic control mechanism for a straight knitting machine having longitudinally movable yarn carrier supporting members, the combination comprising a driving member rotatably mounted for oscillating movement, a plurality of clutch bands for selectively gripping said driving member in driving relation, two separate pattern mechanisms, and a series of control members for effecting selective driving engagement between said clutch bands and said driving member, said control members being adapted to be operated by both of said pattern mechanisms.

15. A straight knitting machine carrier bar operating mechanism comprising two rotary devices, means for driving said rotary devices simultaneously in opposite directions, means for transmitting the drive of one of said devices to at least one carrier bar of the knitting machine, and means for transmitting the drive of the other of said devices to at least one other carrier bar of the knitting machine.

16. In a mechanism for operating carrier bars of a straight knitting machine, the combination comprising two rotary devices, means for oscillating said rotary devices simultaneously in opposite directions, and at least one carrier bar driving element for each of said devices and adapted to be driven thereby.

17. In a mechanism for operating carrier bars of a straight knitting machine, the combination comprising two rotary devices, means for oscillating said rotary devices simultaneously in opposite directions, a plurality of rotary friction clutch bands mounted on each of said rotary devices and adapted to be driven thereby, and means for each of said elements to transmit the drive thereof to an individual carrier bar.

18. In an automatic control mechanism for the movable yarn carrier bars of a straight knitting machine, the combination comprising carrier bar driving means, frictional clutch devices adapted to be positioned at a single control station on

the knitting machine for operatively and selectively connecting each carrier bar to said driving means, stops for said carrier bars, control rods for selectively operating said stops and said devices, pattern-actuated levers for determinedly operating said control rods, and a single pattern mechanism for selectively operating said levers.

19. In an automatic yarn-feeding control mechanism for a straight knitting machine having a plurality of movable yarn carrier supporting elements, the combination comprising driving means for said elements, devices for operatively connecting each of said elements to said driving means, at least one stop for each of said elements, a set of control rods for each of said elements, each set including a control rod for the connecting device and a control rod for each stop of the respective element, a movable pattern mechanism having a row of pattern-determining members arranged lengthwise thereof for each set of control rods, and operating connections between each row of said members and its set of control rods for determinedly actuating the device and the stop of the respective yarn carrier supporting element upon movement of said pattern mechanism.

20. In an automatic control mechanism for the movable yarn carrier supporting members of a straight knitting machine, the combination comprising driving means, a plurality of clutch devices for operatively and selectively connecting each of said yarn carrier supporting members to said driving means in driving relation, stops for said yarn carrier supporting members, a separate control element for each of said devices and stops, and a single pattern mechanism for selective engagement with said control elements to operate the same in a predetermined sequence.

21. In an automatic yarn-feeding control mechanism for a straight knitting machine having a plurality of movable yarn carrier supporting members, the combination comprising driving means, a plurality of clutch devices for selectively connecting said yarn carrier supporting members to said driving means in driving relation, at least one stop for each of said yarn carrier supporting members, a separate control element for each of said devices and stops, a pattern mechanism having a row of pattern determining elements for each yarn carrier supporting member, each of said rows of pattern determining elements being adapted to engage and operate in predetermined order the control elements for the respective yarn carrier supporting member.

22. In an automatic control mechanism for the movable yarn carrier supporting elements of a straight knitting machine, the combination comprising stops for maintaining said elements in stationary position, rotary frictional clutch devices oscillatable simultaneously in opposite directions for shifting said elements, connections providing one-way drives between said clutch devices and said elements, pattern controlled means for selectively operating said stops to release individual supporting elements, and means for driving said clutch devices to shift released supporting elements.

23. In a straight knitting machine wherein the yarn carrier supporting elements are reciprocable over a certain distance for yarn laying operations and are movable to a further extent in one direction to place their yarn carriers in an idle out-of-the-way position spaced from the outermost selavage position, the combination compris-

ing means for releasably locking the individual carrier bars in their idle position, means for shifting released carrier bars from idle to selvage positions, means for reciprocating shifted carrier bars for yarn laying movement, and pattern controlled means for operating said locking, shifting, and reciprocating means in determined order.

24. In a straight knitting machine, the combination comprising a plurality of carrier bars arranged in two sets in their idle position, said two sets being movable in opposite directions when shifted from idle to operative position, means for releasably locking the individual carrier bars in the idle position, a set of friction devices for driving each set of carrier bars from idle to operative position, one-way driving connections between the friction devices and the carrier bars driven thereby, and means for operating the two sets of friction devices simultaneously in opposite directions.

25. In a straight knitting machine, the combination comprising a plurality of movable yarn carrier supporting elements arranged in two sets in their idle position, said two sets being movable in opposite directions when shifted from idle to operative position, means for releasably locking the individual supporting elements in their idle position, a pair of oscillatable driving drums having simultaneous operation in reverse directions, means interposed between each of said drums and one of said sets of supporting elements to provide one-way driving connections for shifting released supporting elements from idle to operative positions, and means for reciprocating shifted supporting elements for yarn laying movement.

26. In a control for the movable elements supporting the yarn carriers of a straight knitting machine, the combination comprising means for releasably locking a yarn carrier supporting element in idle position, an oscillatable member, means for oscillating said member, means frictionally engaging said member and providing a one-way driving connection for said supporting element and operative to shift the same from idle to operative position when released by said locking means.

27. In an automatic control and driving mechanism for a plurality of movable yarn carrier supporting elements in a straight knitting machine, the combination comprising means for locking each of said yarn carrier supporting elements in an idle position, means for controlling said locking means to selectively release the individual yarn carrier supporting elements in a predetermined order, and means for actuating released supporting elements, said actuating means including a rotary device and a plurality of independently movable clutch units for frictionally engaging said rotary device in yielding driving relation, each clutch unit being associated with an individual yarn carrier supporting element to actuate the same after release thereof by said locking means.

28. In an automatic control mechanism for carrier bars of a straight knitting machine wherein the carrier bars are reciprocable over a certain distance to provide the yarn carriers supported thereby with a normal range of movement for yarn laying operations, and each carrier bar is movable to a further extent in one direction to place the yarn carriers thereof in an idle out-of-the-way position beyond and spaced from their normal range of movement, the combination comprising means for selectively reciprocating

ing the individual carrier bars, a set of stops for each carrier bar to limit the reciprocable movement thereof and determine the normal range of movement of the yarn carriers thereof, means for operating one of the stops in each of said sets to permit the corresponding carrier bar to travel to an idle position and place each yarn carrier thereof in its said idle out-of-the-way position, stops for locking each carrier bar in the idle position thereof to maintain the yarn carriers beyond their range of yarn laying movement, means for selectively operating said locking stops to release individual, idle carrier bars, and pattern mechanism for controlling all of said means to provide automatic operation of said carrier bars, said operable limit stops, and said locking stops in determined sequence.

29. The combination with an automatic control mechanism as described in claim 28, of at least one adjustable narrowing head carrying at least certain of said operable limit stops and at least certain of said locking stops, and flexible operating connections forming at least part of the means for selectively operating said narrowing head stops to permit relative translational movement of said narrowing head with respect to the pattern mechanism without interference with the normal operation of said narrowing head stops.

30. In an automatic control mechanism for carrier bars of a straight knitting machine, wherein the carrier bars are reciprocable over a certain distance and between selvage positions for yarn laying operations, and each carrier bar is movable to a further extent in one direction to an idle position for placing the yarn carriers supported thereby in an idle out-of-the-way position spaced from the outermost selvage position thereof, the combination comprising means for locking each carrier bar in its said idle position, pattern mechanism for controlling said locking means to selectively release the individual carrier bars for movement, and means for automatically moving a released carrier bar from idle to selvage position.

31. In an automatic control mechanism for carrier bars of a straight knitting machine, wherein the carrier bars are reciprocable over a certain distance and between selvage positions for yarn laying operations, and each carrier bar is movable to a further extent in one direction to an idle position for placing the yarn carriers supported thereby in an idle out-of-the-way position spaced from the outermost selvage position thereof, the combination comprising means for locking each of a plurality of carrier bars in said idle position, pattern mechanism for controlling said locking means to selectively and individually release the locked carrier bars, means for automatically moving a released carrier bar from idle to selvage position, and means for arresting a released and moving carrier bar at said last-named selvage position.

32. In an automatic control mechanism for carrier bars of a straight knitting machine, wherein the carrier bars are reciprocable over a certain distance and between selvage positions for yarn laying operations, and each carrier bar is movable to a further extent in one direction to an idle position for placing the yarn carriers supported thereby in an idle out-of-the-way position spaced from the outermost selvage position thereof, the combination comprising means for locking each carrier bar in said idle position, pattern mechanism for controlling said locking

means to selectively release the individual carrier bars, means for automatically moving released carrier bars from idle to selvage position, and separate means for operating released carrier bars for yarn laying movement and between selvage positions.

33. In an automatic control mechanism for carrier bars of a straight knitting machine, wherein the carrier bars are reciprocable over a certain distance and between selvage positions for yarn laying operations, and each carrier bar is movable to a further extent in one direction to an idle position for placing the yarn carriers supported thereby in an idle out-of-the-way position spaced from the outermost selvage position thereof, the combination comprising means for locking each carrier bar in its idle position, pattern mechanism for controlling said locking means to selectively release the individual carrier bars, means for automatically moving released carrier bars from idle to selvage position, means for arresting released carrier bars at the selvage position, means for withdrawing said arresting means to an inoperative position, and separate means for operating released carrier bars for yarn laying movement upon withdrawal of said arresting means.

34. In an automatic control mechanism for carrier bars of a straight knitting machine, wherein the carrier bars are reciprocable over a certain distance and between selvage positions for yarn laying operations, and each carrier bar is movable to a further extent in one direction to an idle position for placing the yarn carriers supported thereby in an idle out-of-the-way position spaced from the outermost selvage position thereof, the combination comprising means for reciprocating said carrier bars, means for selectively arresting each of said carrier bars in one direction of movement to stop the carrier bars in a selvage position, means for selectively withdrawing said arresting means to permit additional movement of reciprocating carrier bars in said direction to place the yarn carriers thereof in said yarn carrier idle position, means for automatically locking the carrier bars in said carrier bar idle position at the end of said additional movement, and pattern mechanism for controlling said locking means to selectively release locked carrier bars.

35. In an automatic control mechanism for a straight knitting machine, wherein a plurality of carrier bars are reciprocable over a certain distance and between selvage positions for yarn laying operations, and each carrier bar of said plurality is movable to a further extent in one direction to an idle position for placing the yarn carriers supported thereby in an idle out-of-the-way position spaced from the outermost selvage position thereof, the combination comprising means for reciprocating said carrier bars, means for selectively arresting each of said carrier bars in one direction of movement to stop the carrier bars in a selvage position, means for selectively withdrawing said arresting means to permit additional movement of reciprocating carrier bars in said direction to place the yarn carriers thereof in said yarn carrier idle position, means for automatically locking carrier bars in said carrier bar idle position at the end of said additional movement, and pattern mechanism for controlling said reciprocating means, said withdrawing means, and said locking means to provide operation of the carrier bars in predetermined order.

36. In an automatic yarn feeding control

mechanism for a straight knitting machine, wherein an element supports one or more yarn carriers and is reciprocable to effect reciprocation of said yarn carriers over a normal range of movement for yarn laying operations, said element being further movable in one direction to place said yarn carriers in an idle out-of-the-way position beyond said normal range of movement, the combination comprising means for driving said yarn carrier supporting element, means for limiting the yarn laying movement of said element in one direction of travel, means for locking said element with said yarn carriers in said idle position, means for operating said locking means to release said element, pattern mechanism, and means controlled by said pattern mechanism for operating said driving means, said limiting means, and said releasing means in predetermined order.

37. In an automatic yarn feeding control mechanism for a straight knitting machine, wherein an element supports one or more yarn carriers and is reciprocable to effect reciprocation of said yarn carriers over a normal range of movement between selvage positions for yarn laying operations, said element being further movable in one direction to place said yarn carriers in an idle out-of-the-way position beyond said normal range of movement, the combination comprising means for driving said yarn carrier supporting element, means for limiting the yarn laying movement of said element in one direction of travel, means for locking said element with said yarn carriers in said idle position, means for operating said locking means to release said element, means separate from said driving means for shifting said element when released to return each yarn carrier to a selvage position, pattern mechanism, and means controlled by said pattern mechanism for operating said driving means, said limiting means, and said releasing means in predetermined order.

38. In an automatic yarn feeding control mechanism for a straight knitting machine, wherein an element supports one or more yarn carriers and is reciprocable to effect reciprocation of said yarn carriers over a normal range of movement for yarn laying operations, said element being further movable in one direction to place said yarn carriers in an idle out-of-the-way position beyond said normal range of movement, the combination comprising means for driving said yarn carrier supporting element, a stop for limiting the yarn laying movement of said element in one direction of travel, a stop for locking the element with its yarn carriers in said idle position, pattern mechanism, and means controlled by said pattern mechanism for operating said driving means, said limiting stop, and said locking stop in predetermined order.

39. A carrier bar control mechanism for a straight knitting machine, said mechanism comprising yarn carrier driving means, means movable between inoperative and operative positions to control said driving means and also movable along a predetermined path during the yarn carrier driving operation, means for actuating said control means from one of said positions to the other position and for maintaining the same in the latter position, and means for operating said actuating means to initiate and terminate yarn laying operations.

40. In a straight knitting machine, yarn carrier driving means, pivotally mounted means movable between inoperative and operative posi-

tions to control said driving means and also movable along a predetermined path during the yarn carrier driving operation, means shiftable to actuate said control means to the operative position and to maintain the same in such position for the duration of the yarn carrier operating movement as said control means travels along said path and relative to the actuating means, means for returning said shiftable means to the original position thereof to terminate the yarn carrier driving operation, and means for restoring said control means to the inoperative position during said return movement of said actuating means.

41. In operating mechanism for the yarn carrier bars or supporting elements of a straight knitting machine, the combination comprising rotary driving means, a plurality of individually, radially adjustable means for engaging said rotary means in driving relation, means for transmitting the drive of each of said engaging means to an individual carrier bar, means for each of said engaging means and operable to adjust the same to control the drive thereof, said adjusting means each being movable along a predetermined path during movement of the corresponding carrier bar, means for individually actuating said adjusting means, and pattern means for selectively operating said actuating means to provide operation of the carrier bars in a predetermined order.

42. In operating mechanism for the yarn carrier bars or supporting elements of a straight knitting machine, the combination comprising rotary driving means, a plurality of individually, radially adjustable means for frictionally engaging said rotary means in driving relation, means for transmitting the drive of each of said frictionally engaging means to an individual carrier bar, means for each of said frictionally engaging means and operable to adjust the same to control the drive thereof, said adjusting means being movable along a predetermined path during movement of the corresponding carrier bar, means for actuating each of said operable means and slidably engageable therewith to maintain the same in the actuated position for the duration of movement of the corresponding carrier bar, and pattern means for selectively operating said actuating means to provide operation of the carrier bars in a predetermined order.

43. In a controlling mechanism for the drive of a carrier bar of a straight knitting machine, the combination comprising a control lever, a support for pivotally mounting said control lever, said lever and support being movable as a unit along a predetermined path during carrier bar driving operations, means for actuating said control lever relative to said support from an inoperative to operative position and for maintaining the same in the operative position during movement of said unit along said path, and means for restoring said lever to the inoperative position upon release by said actuating means.

44. In a mechanism for driving and controlling a movable yarn carrier supporting element of a straight knitting machine, the combination comprising a driving member rotatably mounted for oscillating movement, means contractible about said driving member from an inoperative position to frictionally grip the same in driving relation, means to provide a driving connection between said contractible means and said yarn carrier supporting element, a movable control member for contracting said contractible means, means

for actuating and engaging said control member to effect driving engagement between said driving member and said contractible means, and means for restoring said control member to inoperative position when released by said actuating means.

45. In a straight knitting machine, an automatic yarn-feeding mechanism comprising a movable yarn carrier supporting element, a driving member, a member having driving connection with said carrier supporting element and adapted to be driven by said driving member, means mounted to move with one of said members and operative to effect driving engagement between said members, and a race adapted to be positioned for operating said means and for engaging said means during its movement to maintain said means in operative position.

46. In a straight knitting machine, an automatic yarn-feeding mechanism comprising a movable yarn carrier supporting element, an oscillating driving member, a member having driving connection with said carrier supporting element and adapted to be driven by said driving member, means operative to effect driving engagement between said members, said means being mounted to move with one of said members and in an arcuate path, and an arcuate race for engaging said means during its movement to maintain said means in operative position.

47. In a straight knitting machine, an automatic yarn-feeding mechanism comprising a movable yarn carrier supporting element, an oscillating driving member, a member having driving connection with said carrier supporting element and adapted to be driven by said driving member, means operative to effect driving engagement between said members, said means being mounted to move with one of said members and in an arcuate path, and means for operating said operative means, said operating means being movable to operate said operative means and to provide an arcuate race for engaging said operative means during its movement to maintain it in operative position.

48. In a straight knitting machine, an automatic yarn-feeding mechanism comprising a movable yarn carrier supporting element, an oscillating driving member, a member having driving connection with said carrier supporting element and adapted to be driven by said driving member, means including a roller and operative to effect driving engagement between said members, said roller being mounted to move with one of said members and in an arcuate path, and means movable to control said operative means, said control means in one position forming an arcuate race for said roller during its movement to maintain said operative means in operative position.

49. In a straight knitting machine having a movable yarn carrier supporting element, an automatic control mechanism for said carrier supporting element comprising an oscillating driving member, a friction band encircling said member and being secured in driving relation to said carrier supporting element, means carried by said band for releasably contracting said band about said member and causing said band to frictionally grip said member in driving relation, and means for actuating said contracting means and providing in its actuating position a race for said contracting means during its movement with said band to maintain said band in contracted position.

50. In a straight knitting machine, yarn carrier driving means, an element operable to control said means and movable therewith, and a race movable to a position in which it operates said element and maintains said element in operative position during its movement with said driving means.

51. In a straight knitting machine, oscillatable yarn carrier driving means, an element for controlling the operation of said means and movable therewith in an arcuate path, and means movable to a position in which it operates said element, said last-named means in such position providing a stationary arcuate race for said element to maintain it in operative position during its movement with said driving means.

52. In a control mechanism for the yarn carriers of a straight knitting machine, the combination comprising yarn carrier operating means, a member for controlling said operating means and movable therewith during yarn carrier driving operations, a stationary support, a set of two oppositely extending arms pivotally mounted on said support, and means connected to said arms for rocking the same about their pivotal axes to move the said arms from an inoperative position to an operative position for actuating said controlling member and maintaining said controlling member in operative condition during operation of said yarn carrier operating means.

53. In a control mechanism for the yarn carriers of a straight knitting machine, the combination comprising yarn carrier operating means, a member for controlling said operating means and movable therewith during yarn carrier driving operations, a stationary support, a set of two oppositely extending arms pivotally carried at their inner ends by said support, a connecting link pivoted to each of said arms, and means for operating said links to simultaneously rock said arms from inoperative to operative position for actuating said controlling member and maintaining said controlling member in operative condition during operation of said yarn carrier operating means.

54. In a control mechanism for the yarn carriers of a straight knitting machine, the combination of a plurality of devices for selectively operating a plurality of yarn carriers, a member for each of said devices to control its operation and movable therewith during the yarn carrier driving operations thereof, a movable race for each of said members, each race being adapted to be positioned for operating its respective member and maintaining the same in the operative position during the yarn carrier driving operation, and pattern controlled means for automatically and selectively controlling the movements of the individual races.

55. In an automatic control mechanism for the movable yarn carrier bars of a straight knitting machine, the combination comprising means for operating said carrier bars, means for selectively connecting said operating means to the individual carrier bars in driving relation, pattern mechanism for controlling said connecting means and having a plurality of pattern determining elements spaced equi-distances apart with respect to the direction of movement of the pattern mechanism, and automatic pattern controlled means for advancing said pattern mechanism the distance between successive pattern determining elements in each of a plurality of successive operations for controlling said connecting means and for advancing said pattern mechanism a less distance to interrupt the control between said pattern mechanism and said connecting means.

56. In an automatic control mechanism for the movable yarn carrier bars of a straight knitting machine, the combination comprising stops for controlling the movements of said carrier bars, pattern mechanism for controlling said stops to selectively release the individual carrier bars, a narrowing head supporting said stops and movable relative to said pattern mechanism in positioning the stops to vary the limits of carrier bar movement, and flexible operating connections between said stops and said pattern mechanism to permit said movement of the narrowing head without interrupting the control of said stops.

57. In an automatic control mechanism for a straight knitting machine having movable yarn carrier bars, the combination comprising a movable narrowing head, a set of carrier bar stops carried by said head, flexible protective conduits having their opposite ends secured respectively to said narrowing head and a stationary part of the machine, and flexible cables within said conduits and movable therewith for selectively operating said stops.

58. In a control apparatus for knitting machines, the combination comprising an operation controlling member having a plurality of positions of adjustment, a pattern mechanism, and a lever member connected to said controlling member for adjusting same, said lever member having a pair of operating arms, so arranged with respect to said pattern mechanism as to be engaged and selectively shifted thereby, one of said operating arms when engaged and shifted by said pattern mechanism being adapted to adjust said controlling member in one direction, and the other of said operating arms when engaged and shifted by said pattern mechanism being adapted to adjust said controlling member in another direction.

FRANK G. WEISBECKER.
